UNITED STATES PATENT OFFICE.

KAZIMIER CHROBAK, OF ROSEMONT, WEST VIRGINIA, ASSIGNOR OF ONE-HALF TO
JOHN KRYVOSHEY, OF ROSEMONT, WEST VIRGINIA.

ADJUSTABLE PICTURE-FRAME.

1,341,971.

Specification of Letters Patent.

Patented June 1, 1920.

Application filed February 13, 1920. Serial No. 358,528.

To all whom it may concern:

Be it known that I, KAZIMIER CHROBAK, a citizen of Poland, residing at Rosemont, in the county of Taylor and State of West Virginia, have invented certain new and useful Improvements in Adjustable Picture-Frames, of which the following is a specification.

This invention relates to certain new and 10 useful improvements in adjustable picture frames or the like, and the primary object of the invention is to provide an adjustable picture frame which may be changed easily and quickly from one size to another by the 15 mere operation of swinging members of the frame to inoperative position from an operative one or vice versa.

Another object of the invention is to provide an adjustable picture frame of the 20 above kind which is of extremely simple and durable construction and which embodies a plurality of members which may be selectively related to each other with their ends contacting, means being provided to 25 detachably connect said ends in any of the selected relations of the frame members.

This invention may of course be utilized 30 as a frame for mirrors and for various other purposes, and is consequently not limited to use as a picture frame.

With the above general objects in view and others that will become apparent as the 35 nature of the invention is better understood, the same consists in the novel form, combination and arrangement of parts herein-after more fully described in connection with the accompanying drawings.

In the drawings wherein like reference 40 characters indicate corresponding parts throughout the several views,

Figure 1 is a front elevational view of a picture frame constructed in accordance with the present invention and with the members thereof arranged so as to provide 45 the largest size of frame.

Fig. 2 is a view similar to Fig. 1 with the members of the frame related so as to give the smallest size frame.

Fig. 3 is a view similar to Fig. 2 showing the members of the frame related so as 50 to provide a frame slightly larger than that of Fig. 2 and smaller than that of Fig. 1, namely an intermediate size.

Fig. 4 is a fragmentary elevational view 55 of one corner of the frame with the pivoted

members in full lines in the position which they will assume before the same are swung toward each other as shown by dotted lines in this figure to produce the largest frame of Fig. 1,

Fig. 5 is a fragmentary enlarged view of the top frame member and a corner member which is hinged thereto, said members being broken away to illustrate the separable fasteners carried thereby and the hinge connection between the same,

Fig. 6 is a fragmentary end view of one of the end members of the frame and a portion of a glass plate which may be received thereby, and

Fig. 7 is an enlarged fragmentary perspective view of a portion of the top member of the frame and the corner member which is hinged thereto.

Referring more in detail to the several 75 views, the present invention embodies similar top and bottom strips or members 5 and 6 respectively which are of substantially trapezoidal shape in elevation, and similarly shaped end members 7 which, as shown, are 80 of less length than the top and bottom members 5 and 6. The ends of the end members 7 are provided with countersunk sockets 8, each of which form one member of a separable fastener similar to the type used upon 85 gloves and the like, while the ends of the top and bottom frame members or strips 5 and 6 are provided with studs 9, each of which form the male member of such separable fastener, whereby, when the angular 90 ends of the members 5, 6 and 7 are brought together, the studs 9 enter and are retained in the sockets 8 so as to provide a small frame such as is shown in Fig. 2, it being noted that the inner edges of the members 95 5, 6 and 7 are rabbeted as at 10 for reception of a picture, mirror or the like which is broadly shown at 11 in Fig. 6. To each end of each of the members 5, 6 and 7 and at the acute angled corner thereof as indicated 100 at 12 is hinged a substantially rhomboid shaped corner member 13 having studs 14 at one side and sockets 15 at the other side whereby, when one of the corner members 13 at each corner of the frame is swung inwardly into alinement with the end members 7, the studs 14 of said member 13 will be received by the sockets 8 of the end members 7 and the studs 9 of the members 5 and 6 will be received by the sockets 15 of 110

the members 13 so as to provide an intermediate sized frame as shown in Fig. 3. The corner members 13 are all provided at their outer ends with rabbets 10' which will coincide with the rabbets 10 of the members 5, 6 and 7 when said members 13 are swung inwardly so as to provide for the reception of the member 11 as above mentioned. Also, the members 13 are provided with studs 16 10 at their inner ends for reception within sockets 17 which are provided adjacent the pivotal connections 12 in the members 5, 6 and 7. Similarly, when both corner members 13 at each corner of the frame, are 15 swung inwardly, the studs 9 of the members 5 and 6 will receive the sockets 15 of the members 13 which are hinged thereto, and the sockets 8 of the end members 7 will receive the studs 14 of the members 13 hinged 20 thereto, while the studs 14 of the members 13 which are hinged to the members 5 and 6 will be received by the sockets 15 of the members 13 which are hinged to the end members 7 so as to provide a frame of largest 25 size as shown in Fig. 1. It is noted that when both members 13 at each corner of the frame are in outwardly swung inoperative position as shown by full lines in Figs. 2 and 4, studs 14 of the members 30 13 which are carried by the end members 7 will be received in the sockets 15 of the members 13 which are hinged to the top and bottom members 5 and 6, thus providing a more rigid frame.

35 It is of course to be understood that the intermediate sized frame which is shown in Fig. 3 may be varied in form by swinging the members 13 of the members 5 and 6 into operative position instead of members 13 40 of the end frame members 7. When this is done the frame will be quite narrow and long instead of substantially square as is the case with the frame of Fig. 3.

The use of any means to perform the function 45 of the head and socket separable fasteners shown herein is contemplated and the term "separable fasteners" should accordingly be construed in its broadest sense in fixing the scope of each appended claim.

50 From the foregoing description it is believed that the construction and operation or manner of use and manufacture of the present device will be readily understood by those skilled in the art and the advantages 55 appreciated.

Minor changes may of course be made without departing from the spirit and scope of the invention as claimed.

What I claim as new is:—

60 1. An adjustable picture frame comprising top, bottom and end frame strips of substantially trapezoid shape in elevation and having substantially rhomboid shaped

corner members hinged to the ends thereof at their acute angled corners, and separable 65 fasteners carried by the top, bottom, end and corner members or strips whereby the corner members may be swung to operative positions selectively and connected for providing frames of different sizes, substantially as de- 70 scribed.

2. An adjustable picture frame comprising top, bottom and end frame strips of substantially trapezoid shape in elevation and having substantially rhomboid shaped 75 corner members hinged to the ends thereof at their acute angled corners, separable fasteners carried by the top, bottom, end and corner members or strips whereby the corner members may be swung to operative 80 positions selectively and connected for providing frames of different sizes, and further separable fasteners carried by the top, bottom, end and corner members for retaining said corner members in their outwardly 85 swung inoperative positions.

3. An adjustable picture frame comprising top, bottom and end frame strips of substantially trapezoid shape in elevation and having substantially rhomboid shaped 90 corner members hinged to the ends thereof at their acute angled corners, separable fasteners carried by the top, bottom, end and corner members or strips whereby the corner members may be swung to operative 95 positions selectively and connected for providing frames of different sizes, said top, bottom and end members being rabbeted along their inner edges, and said corner members being rabbeted along their outer ends 100 whereby, when the corner members are swung inwardly to their operative position, the rabbets thereof will coincide with the rabbets of the top, bottom and end members, substantially as described.

105 4. An adjustable picture frame comprising top, bottom and end frame strips, corner members hinged to the ends thereof, and means carried by the top, bottom, end and corner members or strips whereby the corner members may, when swung to operative 110 positions selectively, be connected for providing frames of different sizes.

115 5. An adjustable picture frame comprising top, bottom and end frame strips, corner members hinged to the ends thereof, means carried by the top, bottom, end and corner members or strips whereby the corner members may, when swung to operative 120 positions selectively, be connected for providing frames of different sizes, and means for retaining said corner members in their outwardly swung inoperative positions.

In testimony whereof I affix my signature.

KAZIMIER CHROBAK.
